UNITED STATES PATENT OFFICE.

PETER F. MEENAN, OF DETROIT, MICHIGAN.

SWITCH.

1,409,882.

Specification of Letters Patent. Patented Mar. 14, 1922.

Application filed May 20, 1921. Serial No. 471,040.

To all whom it may concern:

Be it known that I, PETER F. MEENAN, a citizen of the United States, residing at Detroit, in the county of Wayne and State of Michigan, have invented new and useful Improvements in Switches, of which the following is a specification.

This invention relates to improvements in railway switches and has especial relation to means for operating a switch.

An object of the present invention is the provision of a switch operating mechanism which may be controlled from a car while the latter is in motion, the mechanism being so constructed as to permit of the switch being "trailed" by cars traveling in an opposite direction, or operated manually by the insertion of a bar or other device between the switch point and the adjacent rail, in the usual manner.

With the above and other objects in view, the invention further includes the following novel features and details of construction, to be hereinafter more fully described, illustrated in the accompanying drawings and pointed out in the appended claims.

In the drawings:—

Figure 1 is a plan view of a switch showing the application of the invention, the switch actuating disk and adjacent mechanism being shown by dotted lines, the figure further illustrating a car truck in position entering a switch.

Figure 2 is a side elevation of the same with some parts broken away and others shown in section.

Figure 3 is an enlarged transverse sectional view taken on a line with the car engaging lever.

Figure 4 is an enlarged skeleton plan view of the track device, the switch point and the adjacent rail, the carrier plate which carries the track device being shown as transparent, in order to more clearly show the actuating mechanism, the closed position of the switch and its operating mechanism being shown by dotted lines.

Figure 5 is a longitudinal sectional view through the subject matter of Figure 4.

Figure 6 is a transverse section of the same.

Figure 7 is an enlarged vertical section taken through the car carried trip cylinder.

Figure 8 is a diagram showing the arrangement of the car carried air controlled device.

Referring to the drawings in detail, wherein like characters of reference denote corresponding parts, the reference character 10 indicates the rails of a track, in which a switch is included, the switch point being shown at 11. This switch point is pivotally mounted as indicated at 12 upon the top of a casing or housing 13, the said top being flush with the roadway.

Located within the casing 13 is a track device for operating switch point 11, the said device including a disk 14 which is disposed horizontally and rotatably upon a pivot 15 carried by the top of the casing 13. 70 This disk operates within a depression 16 formed in the casing 13 and is provided in its periphery with notches 17, whose adjacent walls 18 are inclined and terminate in a point 19. Eccentrically pivoted to the 75 disk 14 as shown at 20, is one end of a link or arm 21, the opposite end of this link or arm carrying a stud or pin 22, which operates through a slot 23 provided in the top of the casing 13, the said stud or pin being 80 connected to the switch point 11, as shown. By this means, rotation or oscillation of the disk 14 will impart pivotal movement to the switch point 11 to close or open the switch, as will be readily understood.

For the purpose of actuating the disk 14, there is provided a slide 23, which operates in a guide 24 carried by the top of the casing 13. The inner end of this slide has connected thereto one end of a link 25, whose 90 opposite end carries a roller 26 which enters the depression 16 previously mentioned and operates within the notches 17 of the disk 14. A movement of the slide towards the disk will cause the roller 26 to engage and move 95 along the inclined wall 18 of one of the notches 17 and to engage the inner end of the said notch to move the disk upon its pivot, the limit of movement being regulated by means of stops 27. When the disk 100 is moved in one direction, this movement will be sufficient to carry the point 19 beyond the longitudinal center of the slide 23, so that when the slide is again operated inwardly the disk will be in such position that 105 the wall of the other notch 17 will be engaged and the disk reversely operated. A yoke 28 is provided for holding the roller 26 in proper position.

The slide 23 is automatically returned to 110 normal position and for this purpose the said slide carries a rod 29 which is disposed

parallel beneath the slide and operates within a guide 30. A coiled spring 31 surrounds the rod 29 and is positioned between the guide 30 and a shoulder formed on the guide 23. Pivottally connected to the outer end of the slide 23 is one end of a rod 32, the opposite end of the said rod being pivotally and adjustably connected to a lever 34 which is mounted for pivotal movement adjacent the track as shown at 35. The rod 32 may also be spring actuated to return the parts to normal position and for this purpose is surrounded by a spring 36 which is positioned between an abutment 37 carried by the rod 15 and a bearing 38 through which the rod operates.

The lever 34 has its lower end disposed beneath the surface of the roadway within a suitable casing 39, while a casing 40 connects this last mentioned casing with the casing 13 and provides a housing for the rod 32. The upper end of the lever 34 is arranged at right angles and extends through a slot 41 provided in a guide rail 42, the said 20 guide rail being spaced from one of the rails 10 and located in advance of the switch, the right angled portion of the lever 34 providing an operating trigger 43 which is positioned within the space between the rail 80 10 and the guide rail 42. The rail 42 has each of its ends curved outwardly as at 44 to provide an entrance.

The switch is designed for operation by a car in motion and for this purpose various 35 mechanisms may be employed. One of such mechanisms is shown and includes a cylinder 45 which is secured to the frame 46 at the front of a car truck. This cylinder has mounted therein a piston 47, whose rod 48 40 extends downward to provide a trip 49. This rod is normally elevated by means of a spring 50 which surrounds the same and is located within the cylinder 45, while in order to limit the downward movement of the trip, 45 the rod 48 has mounted thereon a flanged wheel 51. This wheel engages one of the rails 10 in a manner to dispose the trip 49 within the space between the rails 10 and 42 so as to locate the said trip in position to engage 50 the trigger 43.

Normally the trip 49 is elevated and in order to depress the same, the cylinder 45 is connected with a suitable source of air supply, for example the air reservoir of an ordinary air brake system, through the medium of a pipe 52. This pipe leads to a three-way valve 53, which is in turn connected to the air cylinder 45 by means of a pipe 54, a similar pipe serving to connect the valve 60 with a similar cylinder 45 upon the opposite

side of the car track so as to provide for operating a switch upon either side of the car.

It is believed that the foregoing description when taken in connection with the accompanying drawings will render the construction, operation and advantages of the invention apparent. It may be here stated however, that the construction of the rack device is such as to permit the switch to be thrown without the operation of the said device. In other words, a bar or other implement may be inserted within the switch to open the same without actuating the slide 23 or its connected parts. This will leave the parts in position to be subsequently actuated by a car mechanism, if desired.

The invention is susceptible of various changes in its form, proportions and minor details of construction and the right is herein reserved to make such changes as properly fall within the scope of the appended claims.

Having described the invention what is claimed is:—

1. The combination with a railway switch, 85 of a horizontally arranged rotatable disk, means operatively connecting the disk with the switch point, a pivotally movable member located adjacent the track, a spring actuated rod having one end adjustably secured to the pivotally mounted member, a slide pivotally secured to the opposite end of the rod, means carried by the slide for engagement with the disk, whereby the latter will be alternately rotated in opposite directions when the slide is operated by a movement of the pivotally movable member and a car carried device for operating the latter.

2. The combination with a railway switch, 100 of a horizontally rotatable disk, means operatively connecting the disk with the switch point, a pivotally movable member located adjacent the track, a spring actuated rod having one end adjustably secured to the pivotally movable member, a slide pivotally 105 secured to the opposite end of the rod, a guide for the slide, an offset portion for the slide, a rod extending from the offset portion and spaced from and parallel to the slide, a guide for the rod, a spring surrounding the slide carried rod and positioned between the guide and the offset slide, means carried by the slide for engagement with the disk, whereby the latter will be alternately rotated in opposite directions when the slide 115 is operated by a movement of the pivotally movable member and a car carried device for operating the latter.

In testimony whereof I affix my signature.

PETER F. MEEANAN.
